[57] ABSTRACT

A circuit that ensures that the rise time of the leading edge of a temperature-compensated word drive current pulse is constant irrespective of drive current pulse amplitude variation with temperature is disclosed. The circuit samples a variable amplitude reference voltage that is generated by a temperature sensor located in a magnetic memory, such as a core, film or plated-wire memory stack, and generates a correspondingly variable amplitude drive current pulse. The circuit includes a current-mirror comprising two directly-coupled-base transistors to ensure proportional current amplification as required by an associated RC charging circuit that controls the drive current pulse generating output transistor. The proportional current amplification provides the necessary variation in the charging current to fully charge the charging capacitor over the same duration irrespective of drive current pulse amplitude. A pre-charging transistor also ensures rapid turn-off of the output transistor to maintain an abrupt trailing edge of the drive current pulse.

CONSTANT RISE TIME CONTROLLER FOR CURRENT PULSE

BACKGROUND OF THE INVENTION

In the prior art it is known that as the temperature within a memory stack changes the operating characteristics of the memory elements that form the memory stack vary. This variation of temperature requires that the operating temperature of the memory stack be monitored and that a corresponding variation in the drive current pulse characteristic utilized to operate the memory elements within the memory stack be varied in a corresponding manner. Such a temperature compensated memory system is disclosed in the J. A. Howe U.S. Pat. No. 3,488,529. Additionally, it is known that a change in the characteristics of the drive current pulse wave form can produce a variation in the wave form of the memory stack output signals derived therefrom causing corresponding problems in selecting the proper strobe time and amplitude characteristics of the output signal as a variation of the wave form characteristics of the drive current signal. Such need for a reliable drive current signal pulse wave form has been recognized by the W. M. Regitz U.S. Pat. No. 3,436,563. However, it has been the prior art practice to use a drive current pulse with a uniformly increasing leading edge. This solution, however, in a temperature compensated memory system induces an error producing drive current signal wave form in that the rise time of the leading edge thereof then varies as a function of the variation of the amplitude of the drive current pulse. This variation in the rise time of the leading edge of the drive current pulse with amplitude of the drive current pulse induces a timing problem with the so-produced output signal in that the strobe pulse is not always timed at the optimum relationship with the so-produced memory stack output signal. Accordingly, it is desirable that the drive current pulse have a leading edge with a constant rise time irrespective of drive current pulse amplitude to ensure optimum operating characteristics of the associated memory system. The present invention is directed towards a circuit that ensures such optimum operating conditions.

SUMMARY OF THE INVENTION

The circuit of the present invention samples a variable amplitude reference voltage that is generated by a temperature sensor located in a memory stack. The circuit then generates a temperature compensated drive current pulse having the necessary variable amplitude and having a leading edge whose rise time is constant irrespective of the drive current pulse amplitude. The circuit utilizes a first path through a plurality of transistors for achieving the desired variation in drive current pulse amplitude with variation in the reference signal that is produced by the temperature sensor and a second rise time control path through a plurality of transistors and a charging capacitor for ensuring a constant rise time in the leading edge of the drive current pulse irrespective of variation in the amplitude of the drive current pulse. The rise time control path is coupled to a current-mirror formed of two directly-coupled-base transistors that ensure proportional current amplification as required by the associated charging capacitor. An additional pre-charging transistor is utilized to ensure that the trailing edge of the drive current pulse has

an abrupt, substantially uniform fall time as is desired for memory system timing.

BRIEF DESCRIPTION OF THE DRAWINGS

5 FIG. 1 is the circuit schematic of the constant rise time controller of the present invention.

10 FIG. 2 is an illustration of the wave form of the drive current pulse generated by the circuit of FIG. 1 whereby the rise time of the leading edge of the drive current pulse is constant irrespective of the level of the drive current pulse amplitude.

15 FIG. 3 is an illustration of the manner in which the diode D_1 of FIG. 1 effects the operation of the circuit thereof.

DESCRIPTION OF THE PREFERRED EMBODIMENTS

With particular reference to FIG. 1 there is presented the circuit schematic of the constant rise time controller of the present invention. The circuit of FIG. 1 samples a variable amplitude reference voltage V_{REF} that is generated by a temperature sensor 10 located in the memory stack of an e.g., plated-wire memory system and couples to load 12 (the drive line selection matrix

25 and the drive lines located in the memory stack) a drive current pulse I_{OUT} whose amplitude corresponds to and varies with the instantaneous amplitude of the reference signal V_{REF} , the rise time of the leading edge of which is substantially constant irrespective of the particular amplitude of the drive current pulse I_{OUT} . The instantaneous amplitude of the reference signal V_{REF} during the duration of the current pulse, t_r , establishes the corresponding amplitude of the relatively constant amplitude drive current pulse I_{OUT} . The pulse length of

30 the drive current pulse I_{OUT} is determined by the length of time switch S_1 is open, while the constant rise time and fall time of the drive current pulse I_{OUT} are determined by circuit parameters. The circuit includes a current-mirror comprised of transistors Q_3 and Q_4 to ensure the proportional current amplification of current I_2 as required by the associated charging circuit, formed of the current I_3 that is proportional to the reference signal V_{REF} , and the capacitor C_1 to charge the charging capacitor C_1 over the same duration, i.e., rise time, irrespective of drive current pulse I_{OUT} amplitude.

35 The circuit is further comprised of a rise time control circuit including a first branch including transistors Q_1 , Q_2 , Q_3 and a second branch including transistor Q_4 , resistors R_7 , R_8 , capacitor C_1 , and diode D_1 and of an amplitude control circuit including transistors Q_1 , Q_5 , Q_6 and load transistors Q_9 - Q_{9n} . Transistor Q_7 is the switching gate that turns the drive current pulse I_{OUT} ON and OFF under control of the circuit timing input 40 represented by switch S_1 while transistor Q_8 functions as a pre-driver for the output stage formed by load transistors Q_9 - Q_{9n} . Transistor Q_7 holds the circuit OFF when switch S_1 is closed and it functions as a pre-driver via diode D_2 to ensure a relatively abrupt trailing edge fall time.

45 The circuit is turned ON at time t_0 by opening switch S_1 , where switch S_1 is normally closed, which turns OFF transistor Q_7 - diodes D_3 and D_4 are anti-saturation diodes to aid transistor Q_7 to turn OFF faster so as to provide an abrupt, sharp initiation of the drive current pulse I_{OUT} . Current I_3 , which is of a constant amplitude (DC) and is proportional to the output of the reference signal V_{REF} of temperature sensor 10, then starts charging capacitor C_1 at a linear rate that is proportional to

he instantaneous amplitude of the reference signal V_{REF} . The voltage across capacitor C_1 is clamped by transistor Q_6 when the voltage across resistors $R_{12} - R_{12n}$ is equal to the reference signal V_{REF} . Because both the rate at which capacitor C_1 charges at and the final level at which the voltage across resistor R_{12} clamps are proportional to the reference signal V_{REF} , the time from when switch S_1 is opened to when the output drive current pulse I_{OUT} achieves its final relatively constant amplitude level remains essentially constant irrespective of the final amplitude level.

CIRCUIT THEORY

Amplitude regulation:

The reference signal V_{REF} appears across the current determining Resistors $R_{12} - R_{12n}$ when transistor Q_7 is OFF, then

$$I_{OUT} = \left(\frac{\beta_9}{\beta_9 + 1} \right) \left(\frac{V_{CC} - V_1}{R_{12}} \right) = \left(\frac{\beta_9}{\beta_9 + 1} \right) \left(\frac{V_{REF} + V_{BE1} - V_{BE5} + V_{BE6} - V_{BE9}}{R_{12}} \right)$$

For $\beta_9 > 1$ and $V_{BE1} + V_{BE6} \approx V_{BE5} + V_{BE9}$

$$I_{OUT} = \frac{V_{REF}}{R_{12}}, \text{ or } I_{OUT} \propto V_{REF}$$

Rise time, control turn-on and turn-off:

$$I_1 = \frac{V_{REF} + V_{BE1} - V_{BE2}}{R_1} \approx \frac{V_{REF}}{R_1}$$

$$I_2 = \left(\frac{\beta_2}{\beta_2 + 1} \right) I_1 \approx \frac{V_{REF}}{R_1}$$

Now Q_3 is connected as a diode to cancel V_{BE4} , so for

$I_2 > I_{BE4}$:

$$I_3 = \frac{I_2 R_3 + V_{BE3} - V_{BE4}}{R_4} = \frac{I_2 R_3}{R_4} \approx \frac{I_2}{R_4} \left(\frac{V_{REF}}{R_1} \right), \text{ or } I_3 \propto V_{REF}$$

Switch S_1 is normally closed, and is preferably a transistor or logic gate, and maintains transistor Q_7 in its conducting or ON state. When transistor Q_7 is ON, it shorts the base electrode of transistor Q_8 to the supply voltage V_{CC} , maintaining transistor Q_8 and transistors $Q_9 - Q_{9n}$ in their non-conducting or OFF state. Now, when switch S_1 is opened, capacitor C_1 starts charging from $[V_{CC} - V_{CE7}]$ towards ground potential. The bias levels of the circuit (resistors $R_1, R_2, R_5, R_6, R_8, R_9, R_{10}, R_{11}$, are all biasing resistors utilized to establish the various bias levels desired) are selected so that $I_{BE} \ll I_3$, so that

$$\begin{aligned} I_4 &\approx I_3 \\ I_3 &\propto V_{REF}, \text{ so} \\ I_4 &\propto V_{REF}. \end{aligned}$$

Now with

$$i = c dV/dt$$

and since

$$\begin{aligned} I_4 &= \text{a constant,} \\ dV_1/dt &= \text{constant} = I_4/C_1 \end{aligned}$$

and therefore

$$dV_1/dt \propto V_{REF}.$$

This relationship implies that if the reference signal V_{REF} doubles in amplitude, the rate of charge of capacitor C_1 doubles and therefore, the time for I_{OUT} to increase from 0 amplitude to its full amplitude level remains constant irrespective of its final amplitude level.

As illustrated in FIG. 2 with a drive current pulse I_{OUT} having a pulse length t_x , in the prior art when there was utilized a linear drive current pulse rise as in the aforementioned W. M. Regitz U.S. Pat. No. 3,436,563, the rise time of the leading edge thereof would vary with change in amplitude such as where it would have a rise time t_r with an amplitude level 14 and a rise time t_s as with an amplitude level 16. This is in contrast to the circuit of the present invention wherein the rise time t_r of the drive current pulse I_{OUT} would be t_r irrespective of the amplitude being of a level 14 or 16.

A diode D_1 is added to provide an initial step in the signal V_1 to offset the value that the signal V_1 must charge to before transistor Q_8 turns ON because of the baseemitter voltage of transistor Q_8 and transistors $Q_9 - Q_{9n}$.

$$\begin{aligned} (V_{CC} - V_1) \text{ just before switch } S_1 \text{ is opened} &= V_{CE7} \\ (\text{Sat}) &\approx 0.3V \end{aligned}$$

$$\begin{aligned} (V_{CC} - V_1) \text{ required to turn ON transistor } Q_8 &= V_{BEQ} \\ + V_{BE9} &\approx 1.4V \\ (V_{CC} - V_1) \text{ just after switch } S_1 \text{ is opened} &= V_{CE7} \text{ (Sat)} \\ + V_m &= 1.0V \end{aligned}$$

Without diode D_1 in the circuit, capacitor C_1 must charge a total of $1.4V - 0.3V = 1.1V$ before transistor Q_8 turns ON. With diode D_1 in the circuit as illustrated, capacitor C_1 need only charge a total of $1.4V - 1.0V = 0.4V$ before transistor Q_8 turns ON. This relationship is illustrated in detail in FIG. 3 and ensures faster turn-on and more uniform 10% and 90% points in the rise time of the drive current pulse I_{OUT} .

When the level of voltage V_1 changes from

$V_{CC} - V_{CE7}$ to $V_{CC} - V_{REF} - V_{BE1} + V_{BE5} - V_{BE6} - V_{BE9}$, transistor Q_8 clamps the level of voltage V_1 (capacitor C_2 decouples the clamp voltage). This operation clamps the base electrodes of transistor Q_8 and transistors $Q_9 - Q_{9n}$ and initiates the regulated amplitude level or flat-top portion of the drive current pulse I_{OUT} .

To terminate the pulse length of drive current pulse I_{OUT} , switch S_1 is closed at time t_c turning transistor Q_7 ON. This turning on of transistor Q_7 rapidly turns transistors $Q_9 - Q_{9n}$ OFF by charging the bases of transistors $Q_9 - Q_{9n}$ via diode D_2 and turning OFF transistor Q_8 , which will, in turn, hold transistors $Q_9 - Q_{9n}$ OFF. Capacitor C_1 is then discharged through resistor R_7 preparing the circuit for the next cycle as timed by the opening at time t_o and the closing at time t_c of switch S_1 .

What is claimed is:

1. In a controller for maintaining the rise time of the leading edge of an output pulse independently of the amplitude thereof, the combination comprising:

60 a first source of a constant amplitude first reference signal;

a second source of a varying amplitude second reference signal coupled to said first reference signal for controlling said second reference signal to vary its amplitude with respect to said first reference signal;

a plurality of load transistors, each having a control electrode and a pair of output electrodes, having

directly intercoupled control electrodes forming a first node, means coupling each separate first output electrode to said first reference signal and having directly intercoupled second output electrodes; load means coupled to the directly intercoupled second output electrodes of said load transistors; a current-mirror circuit including first and second transistors, each having a control electrode and a pair of output electrodes, with their control electrodes directly intercoupled, and the first output electrode of said first transistor directly coupled to said directly intercoupled control electrodes; a rise time control circuit including first and second branches: said first branch including a third transistor, having a control electrode and a pair of output electrodes for coupling said second reference signal to the first output electrode of said first transistor and generating an amplified first current signal whose amplitude varies as the amplitude of said second reference signal; said second branch including serial coupled first capacitor means and first resistor means coupling said first reference signal to the first output electrode of said second transistor and a second node formed intermediate said first capacitor means and said first resistor means; a fourth transistor, having a control electrode and a pair of output electrodes, means for directly coupling its first output electrode to said first reference signal, means for directly coupling its second output electrode to said second node and means including a first diode means for coupling its second output electrode to said first node; switch means coupled to the control electrode of said fourth transistor and normally keeping said fourth transistor in its conducting state for substantially shorting said second node to said first reference signal as a second current signal flows through the junction of its first and second output electrodes when said fourth transistor is in its normally conducting state or for alternatively charging said first capacitor means at a constant rise time irrespective of the amplitude of said second current signal when said fourth transistor is switched into its non-conducting state.

2. The controller of claim 1 further including a second diode means coupled in parallel across said first resistor means for coupling said first capacitor means to said first reference signal.

3. The controller of claim 1 further including an amplitude control circuit including fifth and sixth transistors, each having a control electrode and a pair of output electrodes, means for coupling the control electrode of said fifth transistor directly to the second output electrode of said third transistor, means for coupling the first output electrode of said fifth transistor directly to the control electrode of said sixth transistor and means for coupling the first output electrode of said sixth transistor directly to said first node, means for coupling the first output electrode of said fifth transistor to said first reference signal and means for coupling the second output electrode of said sixth transistor directly to said first reference signal.

4. The controller of claim 1 further including a seventh transistor having a control electrode and a pair of output electrodes, means for coupling the control electrode of said seventh transistor directly to said second

node, and means for coupling the first output electrode of said seventh transistor directly to said first node.

5. In a controller for maintaining the rise time of the leading edge of an output pulse independently of the amplitude thereof, the combination comprising: a first source of a constant amplitude first reference signal; a second source of a varying amplitude second reference signal coupled to said first reference signal for controlling said second reference signal to vary its amplitude with respect to said first reference signal; a plurality of load transistors having directly intercoupled base electrodes forming a first node, means coupling each separate emitter electrode to said first reference signal and having directly intercoupled collector electrodes; load means coupled to the directly intercoupled collector electrodes of said load transistors; a current-mirror circuit including first and second transistors with their base electrodes directly intercoupled, and the collector electrode of said first transistor directly coupled to said directly intercoupled base electrodes; a rise time control circuit including first and second branches: said first branch including a third transistor coupled in an emitter follower stage and a fourth transistor coupled in a collector loaded stage, said third and fourth transistors cascaded to couple said second reference signal to the collector electrode of said first transistor for generating an amplified first current signal whose amplitude varies as the amplitude of said second reference signal; said second branch including serial coupled first capacitor means and first resistor means coupling said first reference signal to the collector electrode of said second transistor and a second node formed intermediate said first capacitor means and said first resistor means; a fifth transistor, means for directly coupling its emitter electrode to said first reference signal, means for directly coupling its collector electrode to said second node and means including a diode for coupling its collector electrode to said first node; switch means coupled to the base electrode of said fifth transistor and normally keeping said fifth transistor in its conducting state for substantially shorting said second node to said first reference signal as said second current signal flows through its emitter-collector junction when said fifth transistor is in its normally conducting state or for alternatively charging said first capacitor means at a constant rise time irrespective of the amplitude of said second current signal when said fifth transistor is switched into its non-conducting state.

6. In a controller for maintaining the rise time of the leading edge of an output pulse independently of the amplitude thereof, the combination comprising: a first source of a constant amplitude first reference signal; a second source of a constant amplitude second reference signal; a third source of a varying amplitude third reference signal coupled to said first reference signal for controlling said third reference signal to vary its amplitude with respect to said first reference signal;

a plurality of load transistors having directly inter-coupled collector electrodes and having directly intercoupled base electrodes that form a first node; load means for coupling the directly intercoupled collector electrodes of said load transistors to said second reference signal; 5
 first biasing means for coupling the separate emitter electrodes of said load transistors to said first reference signal; a current-mirror circuit including first and second 10 transistors with their base electrodes directly intercoupled, and the collector electrode of said first transistor directly coupled to said directly intercoupled base electrodes; a rise time control circuit including first and second 15 branches: said first branch including a third transistor coupled in an emitter follower stage coupling said third reference signal to the collector electrode of said first transistor for conducting an amplified 20 first current signal whose amplitude varies as the amplitude of said third reference signal; said second branch including serial coupled first capacitor means and first resistor means serially coupling said first reference signal to the collector electrode of said second transistor for conducting an amplified second current signal whose 25 amplitude varies as a function of said first current signal, and a second node formed intermediate said first capacitor means and said first resistor 30 means; an amplitude control circuit including a fourth transistor, means for coupling the emitter electrode of

said third transistor to the base electrode of said fourth transistor, means for directly coupling the collector electrode of said fourth transistor to said first reference signal and means for directly coupling the emitter electrode of said fourth transistor to said first node; a fifth transistor, means for directly coupling the emitter electrode of said fifth transistor to said first reference signal, means for directly coupling the collector electrode of said fifth transistor to said second node, and means including a diode for coupling the collector electrode of said fifth transistor to said first node; a sixth transistor, means for directly coupling the base electrode of said sixth transistor to said second node, means for directly coupling the emitter electrode of said sixth transistor to said first node and means for coupling the collector electrode of said sixth transistor to said second reference signal; switch means coupling the base electrode of said fifth transistor to said second reference signal and normally keeping said fifth transistor in its conducting state for substantially shorting said second node to said first reference signal as said second current signal flows through its emitter-collector junction when said fifth transistor is in its normally conducting state or for alternatively charging said first capacitor means at a constant rise time irrespective of the amplitude of said second current signal when said fifth transistor is switched into its non-conducting state.
